H. ZIMMERMAN

WHEELED WINDMILL TOY

Filed Jan. 26, 1927

FIG. 2.

FIG. 1.

INVENTOR
Harry Zimmerman
By
Maurice Block
ATTORNEY

UNITED STATES PATENT OFFICE.

HARRY ZIMMERMAN, OF NEW YORK, N. Y., ASSIGNOR TO BAR-ZIM TOY MANUFACTURING CO., INC., OF NEW YORK, N. Y., A CORPORATION OF NEW YORK.

WHEELED WINDMILL TOY.

Application filed January 26, 1927. Serial No. 163,593.

This invention relates to wheeled windmill toys and especially to such toys adapted to be drawn along the ground to simulate the action of a windmill.

5 One object of the invention is to produce a toy of this nature of simple and efficient construction that will amuse children.

Another object of the invention is to produce a toy of this nature that is provided 10 with a ground engaging wheel adapted to provide the motive power for rotating a pin wheel comprising a series of vanes radiating from a central hub secured to a shaft rotatably mounted in the upper part of a tower 15 or housing secured to the base of the toy.

A further object of the invention is to provide means in a toy of this nature that will insure contact of the ground engaging 20 driving wheel with the rest of the pin wheel driving mechanism when the toy is propelled along hilly or uneven ground.

Other objects and novel features of construction of my improved toy will become apparent as the specification proceeds.

25 In the drawings forming a part of this specification:

Figure 1 is a front view in elevation of one embodiment of my invention, and

Figure 2 is a sectional view thereof taken 30 on line 2—2, Fig. 1.

Referring to the drawings in detail, in which like numerals refer to the same parts in the various views, 5 indicates a base provided with ground engaging traction wheels 35 6 mounted near the front and rear of the base, on shafts 7 rotatably journaled in the sidewalls of the base. To the underside of the base 5 and centrally located thereon there is secured a bracket 8 provided with an elongated slot 9 in which a stud 10 is loosely mounted and has secured thereto a ground engaging driving wheel 11.

A rotation transmitting member 12 is rotatably mounted on an upright rod or shaft 45 13 secured to the base 5 by means of nuts 14 at the lower threaded end 15 of the rod 13. The rotation transmitting member 12 is provided at its lower end with a disk 16 in contact with the driving wheel 11 and at its 50 upper end with a disk 17 of smaller diameter than the disk 16. A housing 18 in simulation of a windmill tower encloses the rotation transmitting member 12 and is secured to the base 5 by means of screws 19 passing 55 through brackets 20 and the base 5 and by

means of screws 21 passing through the said brackets 20 and the tower or housing 18. A shaft 22 is rotatably and floatingly or swingingly mounted in the upper tower portion 23 and has secured thereto a disk 24 60 in contact with the upper rotation transmitting disk 17. The floating mounting of the shaft 22 is obtained by loosely mounting the shaft 22 in an opening 25 in the tower section 23 and in an elongated slot 26 therein diametrically opposite to the opening 25. The shaft 22 is provided at one of its outer ends with a pin wheel 27 comprising a plurality of vanes 28 radiating from a central portion 29. The pin wheel is 70 maintained on the shaft between two nuts 30 threaded on the shaft 22 and the entire shaft is prevented from becoming displaced by the disk 24 on the said shaft inside the tower and a spacer 31 on the shaft outside 75 the tower.

It will readily be seen that as the toy is drawn along the ground by a pull string 32 secured to one end of the toy, the rotation transmitting member will, due to its own 80 weight, rest on the ground engaging wheel 11 and will be rotated thereby and transmit motion to the pin wheel shaft by means of the disks 17 and 24 and cause the pin wheel to rotate and simulate a windmill in motion. 85 It will also be seen that due to the slots 9 and 29 compensating movement of the various parts is obtained when the toy is drawn along an uneven surface and the said parts will always maintain their proper operative 90 relation.

Having described my invention what I claim as new and desire to secure by Letters Patent is:

1. A toy adapted to be propelled along the ground, comprising a base, ground engaging means on the base, a member on the base provided with a vertically disposed slot, a ground engaging drive wheel rotatably and vertically slidably mounted in the said slot, 95 a shaft secured to the base, a rotation transmitting member resting on the drive wheel and rotatably mounted on the shaft, a housing on the base, a shaft having a pin wheel thereon and rotatably and swingingly mounted in the housing, and a disk on the shaft resting on the transmitting member to be rotated thereby and revolve the pin wheel when the toy is drawn along the ground. 100

2. A toy adapted to be propelled along the 110

ground, comprising a base, ground engaging means on the base, a member on the base provided with a vertically disposed slot, a ground engaging drive wheel rotatably and vertically slidably mounted in the said slot, a shaft mounted on the base, a rotation transmitting member rotatably mounted on the shaft and provided with a lower and an upper contact disk with the lower contact disk thereof in frictional contact with

the drive wheel, a housing in simulation of a windmill tower on the base, a shaft having a pin wheel thereon and swingingly mounted in the housing and a disk on the shaft in frictional engagement with the upper disk 15 of the transmitting member to be rotated thereby and revolve the pin wheel when the toy is drawn along the ground.

HARRY ZIMMERMAN.
